COMBINED BARBER CHAIR AND MIRROR OR SIMILAR ARTICLE

Waddell Goodwin, 326 E. Franklin St.,
Monroe, N.C. 28110

Filed July 30, 1965, Ser. No. 86,363

Term of patent 14 years

(Cl. D15—3)

FIG. 1

FIGURE 1 is a perspective view of a combined barber chair and mirror or similar article showing my new design;

This application is a continuation-in-part of application Ser. No. 83,128 filed Dec. 22, 1964 and entitled Styling Mirror.

I claim:

The ornamental design for a combined barber chair and mirror or similar article, substantially as shown and described.
